UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,215,378.

Specification of Letters Patent. Patented Feb. 13, 1917.

Application filed July 29, 1916. Serial No. 112,043.

To all whom it may concern:

Be it known that I, LEWIS H. JOHNSON, a citizen of the United States, residing at Bloomfield, in the county of Essex and State 5 of New Jersey, have invented certain new and useful Improvements in Telephone-Exchange Systems, of which the following is a full, clear, concise, and exact description.

This invention relates to telephone exchange systems and more particularly to such systems having link circuits which may be employed for indiscriminately interconnecting common battery and magneto or local battery telephone lines terminating at 15 a central office.

The object of this invention is the production of improved signaling means for such telephone exchange systems.

In accordance with a feature of this invention, a link circuit is provided with a relay operating upon connection of the link circuit with a line for causing the energization of another relay, a locking circuit for which is established by the deenergization 25 of the first relay. The deenergization of the locked up relay followed by the energization of a supervisory relay causes a signaling device to furnish an intermittent signal.

30 This invention is illustrated in the accompanying drawing in which all apparatus is shown in its normal and unactuated condition.

There is shown in the drawing a telephone exchange system containing one embodiment of this invention and comprising subscribers' stations A and B connected with lines terminating at a central office, and a universal cord circuit C located thereat for interconnecting the subscribers' stations. It 40 will be understood that a plurality of lines terminate at the central office, but for the sake of simplicity only the two lines are shown. Station A is of the common battery type, while station B is of the magneto type. The universal cord circuit C may be used indiscriminately to connect two magneto telephone lines, two common battery lines or a magneto and a common battery line. It is 45 believed that this invention will be fully understood from a description of the operation of the system shown in the drawing, and it will be so described.

Supposing subscriber A wishes to converse with subscriber B, A will signal the

central office in the usual manner by causing line signal 5 to be lighted. The operator, observing the line signal 5, inserts the answering plug in the jack indicated by this line signal, and thereby causes the operation of a marginal relay 6, relay 7 and cut-off relay 8 over a circuit from battery through windings of relays 6 and 7, sleeve contacts of the answering plug and jack, and the winding of cut-off relay 8 to ground. 60 The operation of the cut-off relay effaces line signal 5. As soon as the answering plug is inserted in the jack of the calling line supervisory relay 11 is operated over a circuit from battery through the winding of 65 relay 11, lower normal contact of relay 45, ring conductor of the cord circuit C, ring contacts of the answering plug and jack, over the line circuit tip contacts of the jack and answering plug, tip conductor of the 70 cord circuit and upper normal contact of relay 45, to ground. The operation of relay 7 causes the operation of a differential listening relay 15 over a circuit from battery through the upper winding of listening relay 15, lower contact of relay 7 and contact 16 of relay 17 to ground. The operation 75 of the listening relay connects the operator's telephone set across the talking strands of the cord circuit. The operation of the listening relay 15 also causes the operation of relay 20 over a circuit from battery through the winding of relay 20, lower alternate contact of relay 15, contact of supervisory relay 11, resistance 9 and alternate contact of 80 relay 6 to ground. The winding of relay 20 is then in parallel with the lamp 10, so that the lamp does not light when the answering plug is inserted in the jack of the calling line. The operation of this relay 85 20 partially completes a locking circuit for itself, the complete locking circuit of which may be traced from battery through the winding of relay 20, alternate contact there- 90 of and contact 21 of relay 15, (which is 95 closed upon the deenergization of relay 15) contact of the supervisory relay 11, resistance 9 and the alternate contact of relay 6 to ground.

Finding the desired number to be that of 105 subscriber B, the operator inserts the calling plug into the jack of B's line, thereby causing the operation of relay 17 and cut-off relay 18 over a circuit from battery through the lower winding of relay 17, lower nor- 110

mal contact of marginal relay 19 and the winding thereof, upper winding of relay 17, sleeve contacts of the calling plug and jack and the winding of cut-off relay 18 to 5 ground.

Relay 19 is marginal and does not operate when in circuit with the cut-off relay of the magneto line, the winding of this cut-off relay being of comparatively high resistance. 10 Relay 17, in operating, opens its normal contact and closes its alternate contacts. The opening of the normal contact removes the short circuit from the lower winding of the differential listening relay 15, whereupon 15 the magnetizing influence of the two windings of this relay neutralize each other so that the relay releases its armatures and disconnects the operator's telephone set from the cord circuit and completes the herein- 20 before described locking circuit of relay 20. The closure of the lower alternate contact of relay 17 causes the operation of relay 25 over a circuit from battery through the winding of relay 25, the upper normal contact of relay 19 and the lower alternate contact of relay 17 to ground. The operation 25 of relay 25 bridges relay 26 across the talking strands of the cord circuit. Subscriber 30 B may be signaled by the actuation of a ringing key 27 which connects a source of ringing current 28 to B's line. Subscriber B, upon removing the receiver from the switchhook in response to the signal, is in direct communication with subscriber A. 35 Upon the completion of the conversation, subscriber A restores his receiver to the switchhook and causes the deenergization of supervisory relay 11, which opens the shunt circuit about the lamp 10, whereupon 40 supervisory lamp 10 lights to furnish a disconnect signal. The circuit for this lamp is from battery through the lamp resistance 9 and the alternate contact of relay 6 to ground. Subscriber B, when the conversation 45 has been completed, gives the crank of his generator 30 a short turn, causing the operation of relay 26, which in turn causes the operation of relay 31 over a circuit from battery through the calling supervisory 50 lamp 32, winding of relay 31 and contact of relay 26 to ground. Relay 31, in operating, establishes a locking circuit for itself from battery through the lamp 32, winding of relay 31, right-hand contact thereof and contact 33 of key 34 to ground. The operation 55 of relay 31 also connects an interrupter 39 in circuit with the resistance 35, both being in parallel with the lamp 32. The lamp 32 will thereby be caused to flash 60 intermittently to furnish a characteristic disconnect signal from the station connected to the magneto line. The operator upon receiving the disconnect signals may withdraw the plugs from the jacks, whereupon 65 all apparatus returns to normal.

However, should subscriber A, before the answering plug is withdrawn from the jack of his line, wish to make a recall, the mere removal of the receiver from the switchhook causes the answering supervisory lamp 10 70 to be lighted intermittently to furnish a recall signal from the station connected with the common battery line. When A restored the receiver to the switchhook, the supervisory relay 11, as before explained, was released, opening its contact. The opening of this contact interrupted the locking circuit of relay 20 which thereupon released. The subsequent energization of the supervisory relay 11, due to subscriber A removing 75 the receiver from the switchhook, connects an interrupter 40 and a resistance 41 in parallel with the lamp 10, whereupon the lamp will be intermittently lighted to furnish the recall signal. The operator, observing the flashing of lamp 10, may actuate the key 34, thereby short-circuiting the lower winding of the differential listening relay 15, permitting this relay to operate to connect the operator's telephone set to the 80 talking strands of the cord circuit. The operation of this listening relay also causes the operation of relay 20 over the herein-before traced circuit. The operation of the listening relay 15 and relay 20 interrupts 85 the shunt circuit of lamp 10, so that the lamp ceases to flash.

Should the originating call be made by a subscriber on a magneto line, the plugging of the answering cord into the jack of such 100 line causes the operation of the cut-off relay associated with that line and relay 7, relay 6 being marginal and operating when in series with the low resistance winding of the cut-off relay associated with the common 105 battery line, but not operating when in series with the high resistance winding of the cut-off relay of a magneto line. The operation of relay 7 causes the operation of relay 45 over a circuit from battery through the winding of relay 45, upper contact of relay 7 and normal contact of relay 6 to ground. The operation of relay 45 bridges relay 46 across the talking strands of the 110 cord. It will be noted that the operation 115 of relay 7 causes the operation of the listening relay in precisely the same manner as when the answering plug is inserted into the jack of a common battery line.

When the calling magneto subscriber 120 gives a disconnect signal, the relay 46 is operated, causing the operation of relay 47 over a circuit from battery through the lamp 10, winding of relay 47 and contact of relay 46 to ground. Relay 47, in operating, 125 establishes a locking circuit for itself from battery through the lamp 10, winding of relay 47, left-hand contact thereof and contact 33 of the key 34 to ground. Interrupter 40 and resistance 41, upon the operation of 130

relay 47, are placed in parallel relation to the lamp 10, whereupon this lamp is lighted intermittently to furnish a characteristic disconnect signal from a station on a magneto line, whereby the operator is furnished a signal of the same character as the recall signal, from a connected common battery line. It will be seen therefore that the operator has to challenge only when observing a 10 flashing signal. If the calling end of the cord circuit be connected with a common battery line, marginal relay 19 will operate, preventing the operation of relay 25 and causing the lamp 32 to be lighted over a circuit from battery through the lamp, lower alternate contact of relay 19, winding thereof, upper winding of relay 17, sleeve contacts of the calling plug and jack and the winding of the cut-off relay to ground.

15 When the called common battery subscriber answers, calling supervisory relay 48 operates, whereupon resistance 35 is placed in shunt of the lamp 32, which is thereby effaced.

20

25 What is claimed is:

1. A telephone exchange system comprising a plurality of subscribers' lines, a link circuit for interconnecting the lines, a supervisory relay and a second relay operating 30 when the link circuit is connected with a calling line, a third relay actuated upon the operation of the supervisory and second relays, a locking circuit for the third relay established upon the deenergization of the 35 second relay, a signaling device, and a source of interrupted current brought into circuit with the signaling device upon the subsequent deenergization of the third relay and the energization of the supervisory relay.

40 2. A telephone exchange system comprising a plurality of subscribers' lines, a link circuit for interconnecting the lines, a supervisory relay and a second relay energized 45 when the link circuit is connected with a calling line, a third relay actuated upon the energization of the supervisory and second relays, a locking circuit for the third relay established upon the deenergization of the 50 second relay, a signaling device and interrupter mechanism, a circuit therefor open at two points, the circuit being closed at one point by the subsequent deenergization of the third relay upon the release of the 55 supervisory relay and closed at the other point by the subsequent energization of the supervisory relay to cause the intermittent operation of the signaling device.

60 3. A telephone exchange system comprising a plurality of subscribers' lines, a link circuit for interconnecting the lines, a supervisory relay for the link circuit, a

supervisory signaling device, an operator's telephone set, a listening relay operating upon connection of the link circuit with a 65 line to include the operator's telephone set in circuit, a third relay energized upon the operation of the listening relay, a locking circuit therefor closed by the deenergization of the listening relay, the deenergization of 70 the supervisory relay causing the deenergization of the third relay, and an interrupter brought into operative relation with the signaling device by the deenergization of the third relay and the subsequent energization 75 of the supervisory relay to cause the signaling device to furnish an intermittent signal.

4. A telephone exchange system comprising a plurality of subscribers' lines, a link circuit for interconnecting the lines, a supervisory relay, an operator's telephone set, a listening relay operating when the link circuit is connected with a line to include the operator's telephone set in circuit, a third relay actuated upon the operation of 80 the listening relay, a locking circuit for the third relay established upon the deenergization of the listening relay, a signaling device, interrupter mechanism brought into operative relation with the signaling device 90 by the deenergization of the third relay and the subsequent energization of the supervisory relay, and an operator controlled key for causing the subsequent energization of the listening relay to interrupt the operative 95 association of the interrupter mechanism and the signaling device and to again include the operator's telephone set in circuit.

5. A telephone exchange system comprising a plurality of subscribers' lines, a link circuit for interconnecting the lines, a supervisory relay, an operator's telephone set, a listening relay operating when the link circuit is connected with a line to include the operator's telephone set in circuit, a third 100 relay actuated upon the operation of the listening relay, a locking circuit for the third relay established upon the deenergization of the listening relay, a signaling device, interrupter mechanism brought into 105 operative relation with the signaling device by the deenergization of the third relay and the subsequent energization of the supervisory relay, and an operator controlled key for causing the subsequent energization of 110 the listening relay to again include the operator's telephone set in circuit, the actuation of the listening relay causing the energization of the third relay to interrupt the operative association of the interrupter mechanism 115 and the signaling device.

In witness whereof, I hereunto subscribe my name this 28 day of July A. D., 1916.

LEWIS H. JOHNSON.
